(57) **CLAIM**

The ornamental design for a beverage container, as shown and described.

DESCRIPTION

FIG. 1 is a top perspective view of a beverage container of the present invention;

FIG. 2 is a bottom perspective view of the beverage container of the present invention;

FIG. 3 is a side elevation view of the beverage container of the present invention, the opposite side elevation view being identical;

FIG. 4 is a front elevation view of the beverage container of the present invention, the rear elevation view being identical;

FIG. 5 is a top plan view of the beverage container of the present invention; and,

FIG. 6 is a bottom plan view of the beverage container of the present invention.

The broken lines showing of the cap and bottom features in all figures are for illustrative purposes only and form no part of the claimed design. The outermost circle shown in a broken line on the bottom of the beverage container, which defines the bounds of the claimed design, forms no part thereof.
